CLAIM

The ornamental design for a display screen with transitional graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1 is a display screen with transitional graphical user interface showing a first image in a sequence of transitioning images; and,

FIG. 2 is the display screen with transitional graphical user interface of FIG. 1 showing a second image in the sequence of transitioning images.

The outermost broken line in each figure illustrates a display screen. The remaining broken lines in the figures illustrate portions of the graphical user interface. None of the broken lines form part of the claimed design.

The appearance of the graphical user interface sequentially transitions between the images shown in FIGS. 1 and 2. The process or period in which one image transitions to another image forms no part of the claimed design.
